ATTORNEY

UNITED STATES PATENT OFFICE

HENRY C. MARCUS, OF SAN FRANCISCO, CALIFORNIA

CIGARETTE BOX

Application filed April 13, 1929. Serial No. 354,841.

This invention relates to a container or box for cigarettes, and especially to one that can be conveniently used in the home or office.

It is well-known that many cigarette smokers have their own favorite brands, and would refuse to smoke any other brands when offered to them by friends. It is one of the objects of my invention to provide a box for holding cigarettes in which partitions are provided for a number of different brands. Thus the person offering the cigarettes can keep these compartments filled with brands and the smoker can choose any of the brands.

In order to facilitate the recognition of the brands in the box, I employ characteristic markings upon the box that can be seen at an appreciable distance; and more particularly, I arrange the markings or labels in such a way that while they appear on an exterior surface of the box, yet they are adjacent the corresponding compartments.

It is also another object of my invention to provide a compact and sturdy box for cigarettes and for matches, that is inexpensive to manufacture.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

Referring to the drawings:

Figure 1 is a perspective view of one form of box utilizing my invention;

Fig. 2 is a top plan view of the same, with the cover removed;

Fig. 3 is a sectional view, taken along plane 3-3 of Fig. 2;

Fig. 4 is a fragmentary sectional view, taken along plane 4-4 of Fig. 2; and

Fig. 5 is a perspective view of the partition forming elements, shown taken apart.

In general, the box can be formed as a conventional rectangular device, having the four sided part 11 appropriately joined together, as by dovetailing. A rabbet is formed around the top edge as by the aid of a thin lining 12 of wood. A top 13 telescopes over the top edge of lining 12, as shown most clearly in Figs. 3 and 4.

In the present instance, there are formed six spaces or compartments, labelled 14, 15, 16, 17, 18, and 19 in Fig. 2, for the accommodation of cigarettes, and a central compartment 20 for the accommodation of matches. In order to form these compartments, I use a central wood block 21 to which the walls forming the compartments can extend. This block is placed in the bottom of the box 11, and can be held in place thereon as by gluing it. In each side thereof there is a groove 22 for the accommodation of the lower edge 23 of the transverse partitions 24. As shown most clearly in Fig. 5, each of these partitions has a projecting part at the lower portion which dovetails into the adjacent groove 22; but other means for joining the parts could obviously be substituted. Furthermore, these transverse partitions extend clear to the lining 12.

Diagonal partitions 25, 26, 27 and 28 extend between the corners of the box and the end faces of the block 21. Gluing can if desired be resorted to for holding these partitions to the lining 12 and also to block 21. Ordinarily however, they can be retained merely by friction. As shown most clearly in Fig. 5, the partitions are of course much deeper vertically than the central block. With all the partitions in place, it is apparent that the spaces 14 to 19 each have an exterior wall formed by the walls of box 11, and on the exterior surfaces, there can be provided labels or legends such as 29, 30, 31 which are intended to correspond with the brand of cigarettes accommodated in the contiguous space. The legends could alternatively be stamped on the exposed top parts of linings 12.

It is apparent that the brands can be thus recognized, even at a distance in this manner. Of course the number of compartments

can be varied to suit requirements, which compartments can all be made to have a wall formed by the exterior walls of the box.

To prevent marring of the furniture upon which the box is placed, I preferably provide resilient pads 32.

In the central space above block 21 matches can be accommodated. A pair of U-shaped blocks 33 can be placed over the block and resting thereon, to define the match space. It is held in place by the inner edges of partitions 24 to 28, as clearly shown in Fig. 2. The matches can be either loosely held in the blocks 33 or else a paper package of matches can be placed. The matches are thus held in a convenient location. Furthermore, the box lends itself readily to artistic treatment, so that it presents a pleasing appearance.

I claim:

- 20 1. In a cigarette box, means forming the exterior walls thereof, a central block, and partitions extending between the central block and the walls to form spaces, said central block having a surface below the top surface of the partitions to form a rest for matches.
- 25 2. In a cigarette box, means forming the exterior walls thereof, a central block, partitions extending between the central block and the walls to form spaces, said central block having a surface below the top surface of the partitions to form a rest for matches, and means held between the partitions and on the block to form a space for the matches.
- 30 3. In a cigarette box, means forming the exterior walls thereof, a central block, transverse partitions dovetailed into the block and extending between it and the walls, said block having a top surface below that of the partitions, diagonal partitions extending between the ends of the block and the walls of the box, and means located between the partitions and on the block for defining a match space.
- 35 4. In testimony whereof I have hereunto set my hand.

HENRY C. MARCUS.
